UNITED STATES PATENT OFFICE.

LOUIS M. ASPINWALL, OF PITTSBURGH, PENNSYLVANIA, ASSIGNOR TO WESTINGHOUSE ELECTRIC & MANUFACTURING COMPANY, A CORPORATION OF PENNSYLVANIA.

MOUNTING OF APPARATUS.

Application filed February 3, 1923. Serial No. 616,765.

To all whom it may concern:

Be it known that I, LOUIS M. ASPINWALL, a citizen of the United States, and a resident of Pittsburgh, in the county of Allegheny and State of Pennsylvania, have invented a new and useful Improvement in the Mounting of Apparatus, of which the following is a specification.

My invention relates to mountings for apparatus and it has special relation to mountings for electrical apparatus in a trolley bus or the like.

An object of my invention is to provide a mounting of the above-indicated character which will permit the easy and speedy interchanging of motors.

Another object of my invention is to provide a vehicle frame adapted to support a motor and control apparatus and which will allow either the motor or the control apparatus to be removed from the end of the vehicle independently of one another.

A more specific object of my invention is to provide a mounting of the above-mentioned character in which the frame of the vehicle is utilized as a support for the motor and control apparatus and also as a guideway to permit sliding the motor and apparatus out of the front of the vehicle.

Other objects, as well as details of construction whereby my invention may be utilized, will be apparent from the following description, taken in conjunction with the accompanying drawings, wherein

Figure 1 is a front view of a portion of a trolley bus or the like, with the front part of the hood removed, and illustrating the preferred form of my invention.

Fig. 2 is a plan view of a portion of the apparatus that is shown in Fig. 1.

Fig. 3 is a view, partly in elevation and partly in section, of the apparatus illustrated in Fig. 1.

Fig. 4 is a view, in front elevation, of a section of the hood shown in Fig. 3, and

Fig. 5 is an enlarged detail view of a portion of the structure illustrated in Fig. 1.

Referring to the drawings, the main frame of the vehicle may comprise channel irons 1. A plurality of supporting brackets or arms 2 of an electric motor 3 are preferably cast integral with the motor frame and, in the preferred form, are disposed, two on one side and one on the opposite side of the

motor, to provide a three-point suspension. 55 The outer ends 4 of the supporting brackets 2 are shaped to conform closely to the inside angle of the channel irons 1 and are adapted to slide along, and be supported by, the bottom flanges 5 thereof. The supporting brackets 2 may be secured to the channel irons 1 by bolts 6.

A pair of supporting members 8, preferably in the form of metal straps, are secured by bolts 9 to the top flanges 7 of the channel irons 1. The supporting members 8 are bent in such manner as to form an arch over the motor 3 for a purpose to be hereinafter set forth. A sheet-metal plate 11 is secured in any suitable manner, for example, by 70 rivets 12, to the straps 8.

Control apparatus 10, comprising a plurality of grid resistors 13 and a plurality of magnetic contactors 14, is secured to the sheet-metal plate 11. 75

A hood 15 is disposed over the motor 3 and control apparatus 10 in the usual manner. A front portion 16 of the hood 15 is adapted to be detachably mounted on the front ends of the channel irons 1 by bolts 80 17, or in any suitable manner and is provided with a ventilating screen 18.

The motor 3 is connected to a drive shaft 19 by a shaft coupling 21 of the usual type.

It will be seen from the above description that, when it is desired to remove the motor 3 from the vehicle for any reason, the front portion 16 of the hood 15 may first be detached from the channel irons 1 by removing the bolts 17. The bolts 6 may be re- 90 moved and the shaft coupling 21 disconnected.

The usual electrical conductors (not shown) leading to the motor may also be disconnected. The motor 3 may then be removed from the front end of the vehicle by 95 sliding the supporting brackets 2 along the bottom flange 5 of the channel irons 1. By reason of the clearance provided by arching the supporting members 8 above the motor 3, the motor may be removed independently 100 of the control apparatus 10. If it is desired to remove the control apparatus 10 from the vehicle, the bolts 9 may be removed, and the control apparatus, mounted upon the sheet-metal plate 11, may be removed by sliding the supporting members 8 along the top flange 7 of the channel irons 1.

It is obvious that the control apparatus 10 may be re- 105

moved independently of the motor 3, if so desired.

It should be understood that the motor 3 and the control apparatus 10 are not a part 5 of my invention and are merely conventionally illustrated.

It will be seen that I have provided a 10 mounting for the motor and control apparatus of a trolley bus, or the like, whereby the removal of the motor or control apparatus 15 may be effected, either together, if desired, or independently of one another, with a minimum expenditure of time and effort.

An advantage of the mounting according 20 to my invention is the facility with which a damaged motor or control apparatus may be replaced by a spare equipment, thus allowing the vehicle to continue in operation while the damaged apparatus is being repaired.

I do not wish to be restricted to the specific structural details or arrangement of parts herein set forth, as various modifications thereof may be made within the spirit 25 and scope of my invention. I desire, therefore, that only such limitations shall be imposed as are indicated in the appended claims.

I claim as my invention:

30 1. In a vehicle, a frame, propelling means comprising a motor and control apparatus therefor detachably mounted upon said frame, and means for sliding said propelling means along said frame out of the front 35 of the vehicle independently of said control apparatus.

40 2. In a vehicle, a frame, a motor and control apparatus therefor mounted upon said frame to permit sliding said control apparatus along said frame to effect the removal thereof from the front of the vehicle independently of said motor.

45 3. In a vehicle, a frame, a motor and control apparatus therefor mounted upon said frame, said motor and control apparatus being adapted to slide along said frame to

effect the removal thereof from the front of the vehicle independently of one another.

4. In a vehicle, a frame comprising a plurality of channel irons, a cover secured to 50 said channel irons, a motor, and a plurality of supporting members secured to said motor and adapted to slide along the bottom flanges of said channel irons to permit the removal of said motor from one end of the 55 vehicle and control apparatus mounted on said cover and removable independently of said motor.

5. In a vehicle, a frame comprising a plurality of channel irons, a substantially arch 60 shaped cover secured to said channel irons, a motor, a plurality of supporting members secured to the motor and adapted to slide along the bottom flanges of the channel irons, means for detachably securing said 65 supporting members to the channel irons, control apparatus removably mounted on said cover and a wall member secured to the front ends of the channel irons, said wall member being detachable to allow the removal of said motor from the front of the vehicle.

6. In a vehicle, a frame comprising a plurality of channel irons, a motor, a plurality 75 of supporting members secured to the motor and adapted to slide along the bottom flanges of the channel irons, auxiliary control apparatus for said motor, supporting means for said apparatus independent of 80 said motor adapted to slide along the top flanges of the channel iron, means for detachably securing said motor and said control apparatus to said frame, and a hood enclosing said motor and control apparatus and having a front portion detachably secured to said frame to permit the removal 85 of said motor and control apparatus from the front of the vehicle.

In testimony whereof, I have hereunto 90 subscribed my name this 25th day of January 1923.

LOUIS M. ASPINWALL.
